UNITED STATES PATENT OFFICE.

SARAH DOROTHY GREENE, OF COXSACKIE, NEW YORK.

DESIGN FOR A COMBINATION SALT AND PEPPER SHAKER.

Application filed April 2, 1928. Serial No. 26,096. Term of patent 3½ years.

To all whom it may concern:

Be it known that I, SARAH DOROTHY GREENE, a citizen of the United States, residing at Coxsackie, Greene County, and State of New York, have invented a new, original, and ornamental Design for a Combination Salt and Pepper Shaker, of which the following is a specification, reference being had to the accompanying drawing forming part thereof.

I claim:

The ornamental design for a combination salt and pepper shaker as shown.

SARAH DOROTHY GREENE.
